UNITED STATES PATENT OFFICE.

LEONARD C. LYZOTTE, OF RICHMOND, VIRGINIA.

PIE-PLATE LIFTER OR HOLDER.

938,258.

Specification of Letters Patent.

Patented Oct. 26, 1909.

Application filed December 29, 1908. Serial No. 469,829.

To all whom it may concern:

Be it known that I, LEONARD C. LYZOTTE, a citizen of the United States, residing at Richmond, in the county of Henrico and State of Virginia, have invented new and useful Improvements in Pie-Plate Lifters or Holders, of which the following is a specification.

This invention relates to a device designed for use in kitchens, bakeries and the like, whereby the housewife, cook or baker, can easily and conveniently remove pies, cakes, etc., from an oven without danger of burning the hands.

The invention has for one of its objects to improve and simplify the construction and operation of devices of this character so as to be comparatively simple and inexpensive to manufacture, reliable and efficient in use, and conveniently manipulated.

Another object of the invention is the provision of a plate holder so designed as to embrace the rim of the plate at opposite points and at the same time engage under the plate to firmly support the latter in removal from an oven to a table or any suitable place.

With these objects in view and others, as will appear as the description proceeds, the invention comprises the various novel features of construction and arrangement of parts which will be more fully described hereinafter and set forth with particularity in the claim appended hereto.

In the accompanying drawings, which illustrate one embodiment thereof, Figure 1 is a perspective view of the device showing the gripping jaws or arms in open position. Fig. 2 is a plan view thereof. Fig. 3 is a central longitudinal section.

Similar reference characters are employed to designate corresponding parts throughout the views.

Referring to the drawing, 1 designates the handle of the device which is preferably a strip of metal of suitable stiffness and formed at its inner extremity with a tongue 2 adapted to engage under and extend diametrically across the bottom of the plate or pan to be removed, the said tongue being offset below the plane of the handle 1 and integrally connected therewith by a connecting portion 3 which forms a shoulder against which the edge or rim of the plate strikes in positioning the device in gripping relation to the plate. The outer end of the handle

is formed into a tooth 4 whereby the device can be hung on a peg or other support.

The device is provided with a pair of arcuate gripping jaws or arms 5 carried by shanks 6 which are preferably a single piece 60 of wire having a coiled spring portion 7 that connects the outer ends of the shank together. The shanks are normally sprung outwardly in divergent relation and on the shanks is a sliding ring or sleeve 8 which, 65 upon movement inwardly, draws the shanks 6 together so as to close the jaws 5 around the plate to be lifted. The jaws are pivotally connected with the handle 1 by a staple 9 fastened to the handle and passing through 70 the coiled portion 7, the staple constituting a pivotal connection between the jaw section of the device and the handle. The jaws 5 constitute portions of the wire forming the shanks 6, and each jaw consists of arcuate 75 bar members 10 and 11 having their outer ends united by a vertical connecting member 12, and the inner end of the member 11 is formed into a vertical portion 13 that is looped at 14 over the bar members 10 where 80 they connect with the shanks 6.

In practice, the device is applied to a plate by first allowing the gripping jaws to spring open by moving the sleeve or ring 8 outwardly toward the coiled portion 7, and then 85 the tongue 2 is inserted under the plate to be removed until the rim of the latter strikes the shoulder or abutment 3. The jaws 5 are then brought into engagement with the plate at diametrically opposite points and 90 the shanks 6 sprung together by sliding the sleeve or ring 8 inwardly toward the jaws. The device is thus locked to the plate so that the latter can be removed without danger of dropping.

It is observed that the slide 8 engages both the shanks 6 of the jaws and the hand member thereby drawing the jaws together and holding the same to the handle member. It is also observed that the slide draws the jaws 100 inward toward the handle member equally so that the pan or pie plate is gripped with equal force.

Having thus described the invention, what I claim is:—

A pan lifter comprising a strip of metal providing a handle member, a pan engaging tongue and a stop, a spring wire doubled upon itself and having a spring coil at the fold, and having the end portions forming 110

2
the straight shanks and jaws, each jaw comprising spaced members and terminal connecting portions, the spaced members being outwardly curved, the said shanks being normally diverged, means engaging the

5 spring coil and connecting the jaws and shanks to the handle member, and a slide engaging both of said shanks and the handle

member and serving to draw the shanks together and hold them to the handle member. ¹⁰

In testimony whereof I affix my signature in presence of two witnesses.

LEONARD C. LYZOTTE.
